UNITED STATES PATENT OFFICE.

KARL LÜDECKE, OF CHARLOTTENBURG, GERMANY, ASSIGNOR TO THE FIRM OF "VEREINIGTE CHEMISCHE WERKE ACTIENGESELLSCHAFT," OF CHARLOTTENBURG, GERMANY.

PROCESS FOR BLEACHING FATS, OILS, RESINS, WAXES, AND THE LIKE.

No. 901,718.

Specification of Letters Patent.

Patented Oct. 20, 1908.

Application filed July 10, 1907. Serial No. 383,013.

To all whom it may concern:

Be it known that I, KARL LÜDECKE, a subject of the King of Prussia, German Emperor, Charlottenburg, Lohmeyerstrasse 1, 5 Kingdom of Prussia, German Empire, have invented new and useful Improvements in Processes for Bleaching Fats, Oils, Resins, Waxes, and the Like, of which the following is a specification.

- 10 The present process for bleaching oils, fats, resins, waxes, yolk, mineral oils and the like, consists in treating the said substances with organic superoxids preferably at temperature of about 100°. The hitherto unknown fact has been demonstrated that the organic superoxids both of the aliphatic and of the aromatic series are soluble in oils, 15 fats, waxes, resins, mineral oils and the like and are precipitated while exerting a bleaching effect, particularly on heating but also in a cold condition. This process presents the special advantage that emulsions, which have hitherto been formed when aqueous bleaches are employed and occasion great 20 difficulties in the manufacture, are entirely avoided. On the contrary the oil remains quite clear; there is no precipitation, formation of salt and so on, so that no filtration or decantation of the bleached oil is necessary. 25 In some cases there has been no complete bleaching but only a change of color. In the subsequent saponification it has appeared, however, that nevertheless a bleaching action has taken place, as the soap obtained is considerably clearer than obtained from untreated oils or fats. Such phenomena are presented by sulfid oil for example. In some cases again it has proved to be advantageous to undertake a further treatment 30 with other purifying agents, such as alkali lye or the like, after the treatment with organic superoxids. The process may also be applied to fatty acids, mineral oils, paraffin and the like.
- 35 The quantity of superoxid employed varies according to the color of the raw material and the color desired for the final product. Generally speaking the quantity of 0.1 to 0.2% has proved to be suitable. Larger or smaller quantities may, however, be employed.

The process is carried into practice by dis-

solving the peroxid, such as benzoyl peroxid for example, in the oil or fat. In the case of solid fats the solution is preferably 55 formed with heating. Such heating may also be effected in the case of liquid fats. Heating is also preferably effected to say 100° C. to 110° C. degrees during the bleaching process. The fat may also be dissolved 60 in a neutral medium such for example as benzin, tetra chlorid of carbon, the peroxid being added to this solution.

All known superoxids have proved to be suitable for example, acetyl superoxid, benzoyl superoxid, acetone superoxid, the oxidation products formed by the action of tetra oxid of nitrogen on organic compounds, which according to recent views must likewise be regarded as superoxids.

Example. 1000 kilograms of red palm oil are melted in a double walled vessel and heated to 100° C. 2 kilograms of benzoyl superoxid are then added gradually while stirring. A solution is soon formed. The 75 mass is then allowed to stand for some time in the heat, during which time the red color changes to a light yellow. According to the nature of the oil, fat, wax or the like used, the quantity of the peroxid employed and 80 likewise the duration of the treatment more or less bleaching is obtained.

What I claim as my invention, and desire to secure by Letters Patent, is—

1. The process for bleaching fats, fatty 85 oils, mineral oils, resins, waxes, paraffin, yolk, fatty acids and the like which consists in dissolving organic superoxids in the material to be bleached and allowing the organic superoxids to act on the material to 90 be bleached.

2. The process for bleaching fats, fatty oils, mineral oils, resins, waxes, paraffin, yolk, fatty acids and the like which consists in dissolving organic superoxids in the material to be bleached and heating the said 95 solution.

3. The process for bleaching fats, fatty oils, mineral oils, resins, waxes, paraffin, yolk, fatty acids and the like which consists in 100 dissolving organic superoxids in a solution of the material to be bleached and heating the said solution.

4. The process of bleaching fats, fatty

oils, mineral oils, resins, waxes, paraffin, yolk, fatty acids and the like which consists in dissolving, without aqueous solutions, organic superoxids in the material to be bleached, avoiding emulsions, and heating the said solution.

In witness whereof I have hereunto signed

my name this 25th day of June 1907, in the presence of two subscribing witnesses.

KARL LÜDECKE.

Witnesses:

HENRY HASPER,
WOLDEMAR HAUPT.
